ARTHUR JAMES TIZLEY, OF NEW YORK, N. Y., ASSIGNOR TO EDWARD F. CALDWELL & CO., OF NEW YORK, N. Y.

OPERATING MEANS FOR ELECTRIC-LAMP SWITCHES.

1,121,420.

Specification of Letters Patent Patented Dec. 15, 1914.

Application filed July 14, 1914. Serial No. 850,894.

To all whom it may concern:

Be it known that I, ARTHUR J. TIZLEY, a subject of the King of Great Britain, and a resident of the city of New York, borough 5 of Brooklyn, in the county of Kings and State of New York, have invented a new and Improved Operating Means for Electric-Lamp Switches, of which the following is a full, clear, and exact description.

10 My invention relates to a means for operating electric lamp switches and it has for its object to provide a rotary lamp switch member with a stud mounted on a leaf spring and movable in a slot in a casing 15 by a cam mounted on a collar so that the switch member may be rotated a distance by the collar and the cam when the collar is rotated in one direction, the leaf spring permitting the stud to move inwardly out 20 of the way when the collar is rotated in the opposite direction. When the switch member is rotated by the engagement of the stud by a cam on the collar, the cam moves the switch member a predetermined distance and 25 with a further rotary movement of the collar, the cam will push the switch into a recess at the end of the slot which permits the cam to pass the stud. The switch member will then be moved back to normal position by a spring provided for this purpose. The rotary switch member having the stud 30 is connected with an electric switch of a well known type.

Additional objects of the invention will 35 appear in the following specification in which the preferred form of my invention is disclosed.

In the drawings similar reference characters refer to similar parts in all the views 40 in which—

Figure 1 is a side elevation of a lamp provided with my improvement; Fig. 2 is an enlarged sectional view showing my improved means for operating the electric 45 lamp switch; Fig. 3 is a sectional view of Fig. 2; and Fig. 4 is an enlarged view showing the switch within the casing.

By referring to the drawings it will be seen that a casing 5 is provided which 50 encloses a switch of a type having a conductor

6 which leads to the lamp 7 and a second conductor with which the switch is connected. The switch is constructed with an insulating member 8 rotatably mounted on the conductor 6, a conducting member 9 being secured to one side of the insulating member 8, this conducting member 9 having portions bent over the periphery of the insulating member 8 at 10 and 11. It will be seen that the insulating member 8 is ratchet 60 shaped and that it is engaged by a spring conducting member 12 so that with the rotary movement of the insulating member 8, the conducting member 12 may be brought into contact with the conducting member 9 65 at 10 or 11 and that with another movement of the insulating member 8 the conducting member 12 will be brought into contact with a surface of the insulating member 8 to open the switch. This is all of a well known 70 construction in which the conducting member 9 is connected with the conducting member 13 to which a binding post 14 is secured.

The conducting member 9 is secured at one side of the insulating ratchet member 8. At 75 the other side of the insulating ratchet member 8 there is secured a plate 15 with ratchet teeth which are engaged by the ratchet plate 16, the ratchet plate 16 being held yieldingly in engagement with the ratchet plate 15 by 80 the spring 17, this spring 17 having an extending terminal 18 secured to the arm 19 mounted on the plate 16. This arm 19 is provided with bifurcated ends 20 between which there is secured an end 21 of the 85 leaf spring 22, a stud 23 being mounted at the outer end of the said leaf spring 22. As will be best seen by referring to Fig. 3 of the drawings, this stud 23 is beveled at 24, so that while the plate 16 may be rotated by 90 the engagement of one of the cams, which will shortly be described, with one side of the stud 23, the cam may engage the other side of the stud 23 to press the said stud inwardly against the resiliency of the spring 95 to permit the cam to pass the stud. The stud 23 is movably disposed in a slot 25 in the casing 5, this slot 25 having a recess 26 adjacent its end 27. It will be understood that by moving the stud 23, the plate 15 will 100

be rotated and with it, the plate 15 carrying the insulating member 8 to bring the conducting member 12 into engagement with the periphery of the insulating member 8, 5 or with the conducting member 9 at 10 or 11 as may be desired, the switch being operated in this manner.

As a means for moving the stud 23, I provide a collar 28 which is rotatably mounted on the casing 5 as shown in the drawings, this collar 28 having cams 29 which are adapted to engage the stud 23 and move it in the slot 25 to the recess 26. When the stud 23 reaches the end 27 of the slot 25, 15 it is pushed into the recess 26 by one of the cams, the cam and the collar 28 being permitted in this manner to continue the rotary movement while the stud 23, with the arm 19 and the plate 16, are rotated by means 20 of the spring 17 to obtain a new engagement with the ratchet teeth on the plate 15 to move again the insulating member 8 when the collar 28 is rotated to bring one of the cams 29 into engagement with the stud 23. 25 When the collar 28 is rotated in the opposite direction, one of the cams 29 will engage the beveled side 24 of the stud 23, which will permit the cam 29 to press the stud 23 through the slot and out of operative position, thereby permitting the collar 28 to rotate without damaging the operative parts 30 of the switch in any manner. The spring 22 permits this movement of the stud 23.

Having thus described my invention, I 35 claim as new and desire to secure by Letters Patent:

1. In a means for operating an electric lamp switch, a rotatably mounted member, a stud, a rotatably mounted cam for operatively engaging the stud, a spring mounted on the member to which the stud is secured for holding the stud yieldingly in position to be engaged by the cam and switch means operable by the member.

45 2. In a means for operating an electric lamp switch, a rotatably mounted member, a spring secured to the member, a stud mounted on the spring for operating the member by the spring, the stud being held yieldingly 50 extended by the spring for engagement by a cam, a rotatably mounted collar having a cam with a side for operatively engaging the stud, one of the said stud and cam members having a beveled surface to permit the other 55 side of the cam member to press the stud inwardly against the resiliency of the spring, and thereby pass the stud, and switch means operable by the first mentioned member.

3. In a means for operating an electric lamp switch, a rotatably mounted member, a spring secured to the member, a stud mounted on the spring for operating the member by the spring, the stud being held

yieldingly extended by the spring for engagement by a cam, a rotatably mounted collar having a cam with a side for operatively engaging the stud, one of the said stud and cam members having a beveled surface to permit the other side of the cam member to press the stud inwardly against the resiliency 65 of the spring and thereby pass the stud, switch means operable by the first mentioned member, and means for returning the first mentioned member to normal position, after rotation by the said cam.

4. In a means for operating an electric lamp switch, a rotatably mounted member, a leaf spring secured to the member, a stud mounted on the spring for operating the member by the spring, the stud being held 80 yieldingly extended by the spring for engagement by a cam, a rotatably mounted collar having a cam with a side for operatively engaging the stud, one of the said stud and cam members having a beveled surface to permit the other side of the cam to press the stud inwardly against the resiliency of the spring 85 and thereby pass the stud, and switch means operable by the first mentioned member.

5. In a means for operating an electric lamp switch, a rotatably mounted member, a spring secured to the member, a stud mounted on the spring for operating the member through the spring, a casing having a slot with a recess at one side and adjacent 90 an end of the slot, the stud being held yieldingly extended through the slot by the spring for engagement by a cam, a collar for rotating relatively to and coaxially with the casing, the collar being provided with a cam 100 having a side for operatively engaging the stud for moving the stud in the slot and from the slot into the recess out of the path of the stud, one of the said cam and stud members having a beveled surface to permit of the 105 opposite side of the cam to press the stud inwardly against the resiliency of the spring and thereby pass the stud, and switch means operable by the first mentioned member.

45 6. In a means for operating an electric lamp switch, a rotatably mounted member, a spring secured to the member, a stud mounted on the spring for operating the member through the spring, a casing having a slot 110 with a recess at one side and adjacent an end 115 of the slot, the stud being held yieldingly extended through the slot by the spring for engagement by a cam, a collar for rotating relatively to and coaxially with the casing, the collar being provided with a cam having 120 a side for operatively engaging the stud for moving the stud in the slot and from the slot into the recess out of the path of the cam, one of the said stud and cam members having a beveled surface to permit of the opposite 125 side of the cam member to press the stud

inwardly against the resiliency of the spring and thereby pass the stud, switch means operable by the first mentioned member, and means for returning the rotary member and
5 the stud to normal position after rotation by the movement of the said cam.

In testimony whereof I have signed my

name to this specification in the presence of the two subscribing witnesses.

ARTHUR JAMES TIZLEY.
